UNITED STATES PATENT OFFICE.

MYRON STANLEY CADWALLADER, OF OLEAN, NEW YORK.

ADJUSTABLE BOOT AND SHOE LAST.

Application filed February 21, 1922. Serial No. 538,277.

To all whom it may concern:

Be it known that I, MYRON S. CADWALLADER, a citizen of the United States, residing at Olean, in the county of Cattaraugus and State of New York, have invented certain new and useful Improvements in Adjustable Boot and Shoe Lasts, of which the following is a specification, reference being had therein to the accompanying drawings.

10 This invention relates to adjustable boot and shoe lasts, and the object of the invention is the construction of a simple and efficient last which is provided with means for efficiently stretching the toe portion of the boot or shoe.

Another object of the invention is the provision of simple and efficient toe jaws adjustably mounted on arms of the last, whereby the extreme outer end of the toe of a boot or shoe can be stretched, or the whole toe portion stretched, just as the operator prefers.

With these and other objects in view, my invention comprises certain novel combinations, constructions and arrangements of parts as will be hereinafter described, illustrated in the accompanying drawings, and more particularly pointed out in the appended claims.

30 In the drawings:

Figure 1 is a top, plan view of a device constructed in accordance with the present invention, showing the same in an extended position.

35 Figure 2 is a top, plan view of the device, showing its arms and toe jaws in a closed position.

Figure 3 is a sectional view, taken on line 3—3, Fig. 1, and looking in the direction of the arrows.

40 Figure 4 is a sectional view, taken on line 4—4, Fig. 3, and looking in the direction of the arrows.

Figure 5 is a sectional view, taken on line 45 5—5, Fig. 3, and looking in the direction of the arrows.

Referring to the drawings by numerals, 1 designates a frame which is provided with a longitudinally-extending slot 2, in which 50 extends bar 3 that has teeth 4 formed in its upper face. Fastened to the outer end of bar 3 is heel jaw 5, which engages the heel portion of a slipper, or shoe, or boot. Formed upon the frame 1 is an apertured head 6, through which head 6 extends the threaded rod 7; on the outer end of rod 7

is a grip 8. Integral with the frame 1 and head 6, and formed behind the head, is a bifurcated extension 9, in which rests the threaded sleeve 10; said sleeve is provided at its inner end with an enlarged portion 11. The enlarged portion 11 is positioned between extension 9 and head 6, and the rod 7 is threaded through the sleeve, Fig. 3, whereby the rod 7 may be adjusted or moved back and forth, through the head 6, by turning the rod. Formed upon the frame 1, and in front of head 6, is a pair of flanges 12, which are beveled, at 13, on their inner faces, so as to allow easy adjustment of the casing 14, between flanges 12. A head 15 is formed on the inner end of threaded rod 7, and this head 15 is positioned in socket 16 of the casing 14, whereby, when the rod 7 is threaded through sleeve 10, longitudinal adjustment of the casing 14 will be caused upon the frame 1. A V-shaped block 17 is fastened to the top of frame 1 contiguous to the outer ends of flanges 12, and U-shaped guides 18 are fastened at their outer ends to the top of block 17, and at their inner ends to the top of the outer ends of the flanges 12. Outwardly-curved arms 19 are pivotally connected at their inner ends to the outer end 70 of casing 14. These arms extend under the U-shaped guides 18, and are adapted to engage the V-shaped block 17.

A pair of toe jaws 20 are used, and each jaw 20 is similarly constructed. Each jaw 20 comprises a body having in its inner face an elongated slot 21, this slot terminating in an upper groove 22 and a lower groove 23 (Fig. 5) in the body in which the ends of pins 24 extend or slide. Pins 24 are placed 80 in the outer ends of the arms 19 by dropping the pins first through the apertures 25, of the jaws, then forcing the pins through suitable apertures in the ends of the arms 19. The advantage of having the outer ends 100 of the arms 19 adjustably positioned in the slots 21 of the toe jaws, resides in the fact that if only the extreme outer end of the toe of the boot, or shoe, has to be stretched, by forcing the arms to the extreme outer ends 105 of slots 21, and then rotating the rod 7, the pressure will be brought to bear only upon the extreme outer ends of the toe jaws, whereas, by moving the outer ends of the arms 19 backward, and then operating the 110 rod 7, the pressure will be exerted more upon the entire length of the toe; sometimes

it is only desired to stretch the extreme inner end of the toe of the boot, or shoe, and then, at other times, it is desired to stretch the entire toe portion of the boot, or shoe, 5 and these different needs or conditions will be satisfied by using my device.

A pivoted latch 26 is mounted, at 27, upon the outer face of the bifurcated extension 9, and this latch, when in its closed position 10 (Fig. 4), engages one of the teeth 4 of bar 3, the latch being held in position against extension 9, by pin 28. This latch 26 fastens the bar 3 in an extended position, but by raising upward upon the latch, the bar 3 15 can be moved or forced inwardly upon frame 1. By reason of the adjustability of heel jaw 5 and bar 3 upon the frame 1, as well as the adjustability of arms 19 and toe jaws 20, my device can be quickly applied to dif- 20 ferent-sized slippers, shoes, or boots.

While I have described the preferred embodiment of my invention, and have illustrated the same in the accompanying drawings, certain minor changes or alterations 25 may appear to one skilled in the art to which this invention relates, during the extensive manufacture of the same and I, therefore, reserve the right to make such alterations or changes as shall fairly fall within the 30 scope of the appended claims.

What I claim is:

1. In a device of the class described, the combination of a frame provided with an apertured head and with a bifurcated extension 35 tension, a sleeve in said bifurcated extension and provided at its inner end with an enlarged portion positioned between the bifurcated extension and the head, a rod threaded through said sleeve and head, toe 40 jaws, means connecting said toe jaws to said rod, and a heel jaw adjustably mounted upon said frame.

2. In a device of the class described, the combination of a frame provided with 45 flanges and a block, guides connected to said block and flanges, a casing slidably mounted between said flanges, arms between the block and flanges and under said guides and connected to said casing, toe jaws on said arms, 50 means for adjusting the casing between said flanges, and a heel jaw attached to said frame.

3. In a device of the class described, the combination of a frame provided with a pair of parallel flanges beveled at their outer 55 ends, a substantially V-shaped block secured to the frame contiguous to the outer ends of said flanges, guide means fastened to the block and to the flanges, a movable casing between said flanges, arms attached to said casing and positioned under said guide means, jaws on said arms, and a heel jaw attached to the rear end of said frame. 60

4. In a device of the class described, the combination of a frame provided with a pair of flanges, a V-shaped block attached to the frame contiguous to the outer ends of said flanges, U-shaped guides having their ends fastened to the block and the flanges, a socketed casing slidably mounted between the flanges, arms under the guides and pivotally connected to the socketed casing, toe 70 jaws carried by the outer ends of said arms, an operating rod seated at its inner end in said socketed casing, and a heel jaw adjustably secured to the rear end of said frame. 75

5. In a device of the class described, the combination with a frame, of toe jaws positioned contiguous to said frame and provided in their inner faces with elongated slots, each toe jaw provided with upper and lower 80 grooves opening upon the slot, each jaw provided with a pin-receiving aperture in its top and opening at its inner end upon the upper groove, arms carried by the frame 85 and extending through the slots, pins in the extreme outer ends of the arms and having their ends in the upper and lower grooves, and means carried by the frame and connected to the arms for adjusting the 90 same upon the frame.

6. In a device of the class described, the combination with a frame, of toe jaws contiguous to said frame, each jaw provided with a slot and with grooves, each jaw provided with a pin-receiving aperture registering with the grooves, arms adjustably mounted upon said frame and extending into said slot and grooves, and pins in the 95 grooves and extending through the arms. 100

In testimony whereof I hereunto affix my signature.

MYRON STANLEY CADWALLADER.
